UNITED STATES PATENT OFFICE.

SOLOMON W. KIRK AND GEORGE R. AYRES, OF PHILADELPHIA, PA.

IMPROVEMENT IN MACHINES FOR PULVERIZING ORES.

Specification forming part of Letters Patent No. **153,172**, dated July 21, 1874; application filed April 2, 1874.

To all whom it may concern:

Be it known that we, SOLOMON W. KIRK and GEORGE R. AYRES, of Philadelphia, county of Philadelphia and State of Pennsylvania, have invented certain Improvements in Machines for Pulverizing Ores, of which the following is a specification:

Our invention relates to the construction of some of the parts, and their combination with other parts, of a machine for grinding and pulverizing ores bearing the precious metals, and for the collection of the ores so pulverized by the use of a draft of either hot or cold air in and as a part of the process.

In the accompanying drawings, Figure 1 represents a central longitudinal sectional view of such an apparatus embracing our improvements; Fig. 2, a front-end view of the same; Fig. 3, a plan view in detail of the feed-hopper portions of the hollow spindle and main cylinder, and a vertical central longitudinal view of the same on an enlarged scale.

The main frame consists of the two end plates K and K' braced together by the four longitudinal rods k' k' k' k'; and in these two end plates the hollow shaft G has its bearings, and upon that shaft is fastened the hollow cylinder A, and at the rear end the joining is water and air tight, but at the front end the attachment to the hollow shaft is by means of radial arms; and the front head of the hollow cylinder A is provided with an extension, H, similar to the hub of a wheel, and into that hub is fitted a funnel-shaped cylinder, D, which incloses the said hollow shaft G, and is supported upon an extension of the front plate K; and into this funnel-shaped cylinder D is fitted the hopper B, which is closed at the top by slide-valve b and at the bottom by slide-valve b'.

By this construction and arrangement of the hollow shaft G, the cylinder A, and the funnel-shaped cylinder D, and the hopper H, the ores, when broken into the size of hens' eggs, and placed in the hopper, and the valve b' removed, find their way into the interior of the cylinder A, and then, by revolving this

cylinder at the rate of fifteen or twenty revolutions per minute, with the aid (or without it) of the iron balls a a a, the pieces of ore are broken and worn down into the form of powder, which floats upon the air.

For the removal and collection of such powder the said shaft G is made hollow, except at the central point g, and thoroughly perforated with small holes g' g' g'; and a blowing apparatus, C, is provided to force a current of air through the hollow shaft G and the cylinder A, as indicated by the arrows in Fig. 1, and out into the receiver F, which is provided with several successive compartments under the same cover, and this current carries along and out with it the pulverized ore, and the same is arrested and confined in the said receiver F; but the blowing apparatus is not set to work until the cylinder A has been sufficiently filled; and then, by means of the two valves b and b', the hopper B is closed against the return of the powdered ore, and its only avenue of escape is through the hollow shaft G into the receiver F. The current of air may be either hot or cold, as may be desired, and by means of it the ore may be thoroughly dried, and in the place of the balls a a a lumps or slugs of any hard material may be used to assist in breaking down the rocks to powder. The funnel-shaped cylinder D is fixed and stationary upon the frame, and by its peculiar form induces the lumps of ore to roll and slide down into the cylinder A through its hub H, which incloses and turns upon it. By means of the pulley I and the gear-wheel M on the same shaft with it the large cog-wheel J is revolved, as well as the hollow shaft G, upon which it is fastened.

In our application for Letters Patent of the United States for an amalgamating apparatus for ores, filed December 18, 1873, we have described and shown a cylinder the same in general form and construction with cylinder A in this our application; and the said cylinder in that other application, like the one in this application, is fixed upon a hollow spindle, which is thoroughly and regularly perforated with holes inside of the large cylinder, except the

central portion, which is solid. We do not in this application make any claim for the said large cylinder and hollow spindle, except that wherein we claim them in combination with other parts, and which were not shown and described in that other application aforesaid; and

What we do herein claim as our invention is—

1. The combination of the large cylinder A, provided with hub H, and attached to and fixed upon the hollow spindle G, and the hub end of the cylinder, provided with feed-openings around the hollow spindle to admit the lumps of ore, and the said hollow spindle G, perforated with holes in a regular manner along its entire length, except a short central portion, which is solid, and the blowing apparatus, substantially as shown and described, for the purpose set forth.

2. The combination of the hopper B, provided with valves b and b', funnel-shaped cylinder D, and cylinder A, as co-operating devices to feed the machine, and to prevent the return of the air driven in by the blowing apparatus, substantially as described and set forth.

3. The combination of the hopper B, provided with valves b and b' inserted into the funnel-shaped cylinder D, and that cylinder mounted and fixed upon the main frame, and supporting the hopper, and having its mouth inserted into the hub H of the cylinder A, and the blowing apparatus C, substantially as and for the purpose described.
